Suncast Wall-Mount Garden Hose Reel, 175 ft. 5/8in. Vinyl Water Hose Holder, Light Taupe, available in Amazon.com, customer review oldest date May 26, 2014[online], [site visited Feb. 27, 2025], Available from the internet URL: <https://www.amazon.com/Suncast-Wall-Mount-Garden-Vinyl-Holder/dp/B00BC3P45U> (Year: 2014).*

Primary Examiner — George J Ulsh*Assistant Examiner* — Kathryn Elizabeth Zieno(74) *Attorney, Agent, or Firm* — Jacob M. Ward; Ward Law Office LLC(57) **CLAIM**

The ornamental design for a hose guide as shown and described.

DESCRIPTION

FIG. 1 is a top perspective view of a hose guide;

FIG. 2 is a bottom perspective view thereof;

FIG. 3 is a front elevational view thereof;

FIG. 4 is a top plan view thereof;

FIG. 5 is a right-side elevational view thereof;

FIG. 6 is a left-side elevational view thereof;

FIG. 7 is a bottom plan view thereof; and,

FIG. 8 is a rear elevational view thereof.

The broken lines shown are for the purpose of illustrating portions of the hose guide and form no part of the claimed design.

1 Claim, 3 Drawing Sheets(56)
